UNITED STATES PATENT OFFICE.

JAMES HENRY MANGAN, OF NEW HAMPTON, IOWA.

RAILROAD-CROSSING SIGNAL.

1,307,916.

Specification of Letters Patent. Patented June 24, 1919.

Application filed January 28, 1916. Serial No. 74,920.

To all whom it may concern:

Be it known that I, JAMES H. MANGAN, a citizen of the United States, residing at New Hampton, in the county of Chickasaw, State of Iowa, have invented certain new and useful Improvements in Railroad-Crossing Signals; and I do hereby declare the following to be a full, clear, and exact description of the invention, such as will enable others skilled in the art to which it appertains to make and use the same.

This invention relates generally to signals, and may be more particularly associated with means for indicating at a railway crossing the approach of trains or cars from either direction.

The primary object of the invention is to provide a signaling mechanism which may be actuated by an oncoming train to warn persons at a distant grade crossing of the approach of the train, and also to operate the signal to indicate "clear" after the train has passed the crossing.

A further object of the invention is to provide a signal of the class described which is capable of indicating to persons at a railway crossing the approach of trains either by day or by night, and which is so constructed that the device will be prevented from becoming deranged or inoperative, either by reason of defective mechanism or from storm or heavy weather.

A still further object of the invention is to provide a device of the character described which is of comparatively simple construction, which is automatic in operation, which is easily installed, which is insured against derangement of the various parts, and which will prove at all times positive and efficient in operation.

With these objects in view, together with others which will appear as the description proceeds, the invention resides in the novel combination and arrangement of parts, all as will be described more fully hereinafter, illustrated in the drawings, and particularly pointed out in the appended claim.

The invention will be best understood by reference to the accompanying drawings, 50 wherein:

Figure 1, is a diagrammatic view of a railway grade crossing, indicating the application of a signaling mechanism constructed in accordance with my invention.

Fig. 2, is an enlarged vertical sectional view taken through one of the signaling

posts employed in carrying out the invention,

Fig. 3, is a sectional view taken substantially upon line 3—3 of Fig. 2, 60

Fig. 4, is a view taken on line 4—4 of Fig. 2, and

Fig. 5, is a sectional view taken on line 5—5 of Fig. 2.

In carrying out the invention, use is made of signal arms mounted upon a roadway adjacent a railroad track, the said signal arms being adapted to be swung across or back from the road accordingly as a train approaches or departs from the crossing 70 with which the signal arm is associated. To this end, upon the roadway adjacent the track a suitable post is mounted, the said post carrying a revoluble shaft supporting a signal arm, the said post being equipped 75 with a motor for rotating the shaft, an electrical connection between the motor and the track whereby contacts depressed by an approaching train will actuate the motor to swing said signal arm in danger position, 80 and contacts located beyond the crossing which may be actuated by the departing train to reverse the motor to swing the signal arm to indicate "clear." In order that the signal may be readily observed after 85 nightfall, an electric lamp may be mounted upon the signal arm, and contacts are arranged within the post whereby the lamp will only be illuminated upon the approach of a train. 90

In further carrying out the invention, a post 6 is secured to extend above the ground adjacent the roadway a suitable distance beyond the railway crossing, the said post being formed at its lower end with a base 7 95 whereby the same may be rigidly anchored to the ground. Mounted in any suitable manner upon the upper end of the post, is a housing 8, the said housing being preferably of greater dimensions than the post 100 for the accommodation of the mechanism for operating the signal. The housing is preferably formed of metal and is securely closed to prevent rain or snow gaining access to the same. A tubular member 9 is secured to 105 project upwardly from the housing 8, the said tubular member being secured to the housing in any preferred manner. Mounted for rotary movement within the tubular member is a shaft 10. This shaft projects 110 at one end into the housing and is supported at the base thereof by a suitable thrust bear-

ing 11, and projects at its opposite end slightly beyond the corresponding end of the tubular member 9. An elbow 12 may be rigidly secured to the latter end of the 5 shaft 10, the said elbow being provided at its lower end with an enlarged head or cap member, from which an annular flange 13 depends. The head or cap is of such diameter as to inclose the adjacent end of the 10 tubular member 9, the said tubular member being provided with a ring 14 within which ball bearings 15 may be arranged. The bearings 15 project slightly beyond the edge of the tubular member and the ring, and support 15 the elbow through the cap. It is apparent that this construction enables the shaft 10 to be freely rotated with the least possible amount of friction. Projecting laterally from the elbow 12, and preferably at 20 such angle as to swing horizontally across a roadway, is a signal arm 16. The said signal arm may be provided with a sign member 17 bearing any suitable warning inscription.

25 As a convenient means for imparting rotary movement to the shaft 10 at predetermined times, a motor 18 is provided, the direction of rotation of said motor depending on the direction of the current. This 30 motor is mounted within the housing 8, and has its gear 19 enmeshing with a gear or segment 20 secured upon the shaft 10. To limit the movement of the shaft 10 in either direction, stops 21 are provided. These 35 stops may be arranged adjacent the base of the shaft 10, and are adapted to be contacted by a projection or lug 22 on the said shaft. The stop arrangement is such that when the signal arm is projected across 40 the road the same will be prevented from further movement, and when the arm has been swung in reverse direction to lie parallel with the road, the opposite stop will operate to limit said movement.

45 In order that the signal will be visible after dark, a lamp 23 is arranged upon the signal arm. This lamp is preferably one of the incandescent type and may be colored red if desired. Wires 24 lead from the lamp 50 through the signal arm 16, bracket 12, and shaft 10, and are connected respectively with contacts 25 and 26 upon the interior of the tubular member and exterior of the shaft 10 respectively. A suitable source of electrical energy, such as a battery 27, is in the 55 lamp circuit, and it will be observed with particular reference to Fig. 4 of the drawing that when the arm 16 is swung to such position as to lie across the roadway the contacts 25, 26 will be engaged and the circuit completed.

60 From the above description, it is apparent that when the motor 18 is energized to rotate its gear 19 in one direction, the shaft 65 10 will be at once rotated to swing the arm

16 across or back from the roadway accordingly as the gear 19 is rotated. Assuming that the arm 16 has been swung to danger position, the same may be retracted or withdrawn from the roadway by reversing the 70 movement of the motor 18. It is also to be observed that upon extreme movement of the arm 16 in either direction, the same will be held against further movement by the stops 21, 22.

75 As an efficient means for actuating the signal automatically upon the approach or departure of a train, contacts may be arranged adjacent the railway rails to be operated upon by the wheels of the cars. A pair of 80 contacts 28 of conventional form are located adjacent each of the railway tracks a suitable distance in advance of the railway crossing. The motor 18 is of that conventional form in which the field is provided with two opposite 85 windings both of which are in series with the armature so that when one field winding is connected through the armature in series with a source of electricity the field will have one polarity to effect rotation of the armature in one direction while when the other 90 winding is in series with the armature and in circuit with the source of electricity, the field will have an opposite polarity to effect opposite rotation of the armature. This 95 type of motor is well known and needs no specific illustration. Leading from the free terminal of one winding of the armature of the motor 18 is a wire 29' that is connected with a wire 29 that connects corresponding 100 contacts of the two pairs of contacts 28 illustrated as associated with the two tracks of the double trackway illustrated in Fig. 1. The other contacts of the two pairs 28 are connected by means of a wire 30 from which 105 leads a wire 30' to one side of a battery 31, the other side of which leads to the free terminal of the armature winding of the motor, the other terminal being of course connected with the mutually connected terminals of the 110 field windings. At the opposite side of the railroad crossing from each pair of the contacts 28 there are arranged, on the corresponding tracks of the double trackway, a pair of contacts 32. One contact of each 115 pair 32 is connected with the corresponding contact of the other pair 32 by means of a wire 33 which is connected by means of a wire 33' with the free terminal of the second field winding. The other terminal of one 120 of the pairs of contacts 32 is connected by a wire 33'' with the wire 30 and thence through the wire 30' to the battery 31 while the corresponding contact of the other pair 32 is connected by a wire 32' to the wire 30 125 and thence through the wire 30' to the battery 31. It will thus be seen that one contact of each pair is in circuit with the same terminal of the battery 31 while the remaining contacts of corresponding pairs are connect- 130

ed with the free terminals of the field windings respectively. Each pair of contacts 38 constitutes a circuit closure for engagement and operation by the wheels of a train passing thereover and each of these circuit closures may have any of the ordinary constructions for holding them closed a sufficiently long time to effect the shifting of the signal. Thermostatically operated cut-outs 10 are common and that type may be used if desired.

It will be seen from the construction of the post for supporting the signal operating mechanism that the same will be insured 15 against access of rain, snow or sleet to the interior thereof. Particular attention in this respect is directed to the specific form of ball bearing joint which I have arranged at the top end of the tubular member 9. It is also 20 apparent that the simplicity of the operating elements of the device insures positive operation at all times, and also renders the liability of derangement of any of the parts exceedingly remote. The diagrammatic view 25 of the wiring and contacts is merely shown for the purpose of indicating a complete signaling system, and it is to be understood that such wiring and contact systems as should be

found desirable may be used instead of the one shown. I am also aware that various 30 changes in the minor details of construction may be made, and I reserve to myself the right to resort to such changes as I may see fit without departing from the spirit of the invention.

I claim:

In a railway crossing signal, a casing, a tubular post extending upwardly from the casing, an annular bearing member at the upper end of the tubular post, a shaft within 40 the tubular post and having bearing engagement in the casing, a tubular elbow member having one end portion threadedly receiving the upper end of the shaft, a signal arm threaded in the other end of the elbow member, 45 a lateral flange on the first specified end of the elbow member in bearing connection with the bearing member of the post, and means within the casing for rotating the shaft in opposite directions.

In testimony whereof, I affix my signature, in the presence of two witnesses.

JAMES HENRY MANGAN.
